DUSTING MOP HEAD

Louis A. Littleton, Davis and Trenton Ave.,
Point Pleasant, N.J. 08742

Filed Feb. 8, 1968, Ser. No. 10,508

Term of patent 14 years

U.S. Cl. D49—21
Int. Cl. D7—06

FIG. 1 is a top plan view of a dusting mop head showing my new design;

FIG. 2 is a bottom plan view thereof;

FIG. 3 is a side elevational view thereof;

FIG. 4 is a front elevational view thereof; and

FIG. 5 is a rear elevational view thereof.

I claim:

The ornamental design for a dusting mop head, substantially as shown.
